UNITED STATES PATENT OFFICE.

FRANK E. BUNDY, OF ELMIRA, NEW YORK, ASSIGNOR TO THE FRANK E. BUNDY LAMP COMPANY, OF SAME PLACE.

ACETYLENE-GAS GENERATOR.

SPECIFICATION forming part of Letters Patent No. 616,889, dated January 3, 1899.

Application filed August 27, 1898. Serial No. 689,690. (No model.)

To all whom it may concern:

Be it known that I, FRANK E. BUNDY, a citizen of the United States, residing at Elmira, in the county of Chemung and State of New York, have invented certain new and useful Improvements in Acetylene-Gas Generators, of which the following is a specification.

My invention relates more particularly to improvements in acetylene-gas generators as 10 described in Letters Patent No. 608,571, is- sued to me on the 9th day of August, 1898, which are adapted for lamps, lanterns, head- lights, and the like, wherein the gas is taken directly from the generating-chamber and 15 delivered to the burner as rapidly as generated.

The object of my invention is to improve and simplify the generator described in the Letters Patent aforesaid, and I accomplish 20 this object by the construction and arrangement of parts as illustrated in the accompa- nying drawing and hereinafter described.

The drawing represents a central vertical section of the generator as adapted for table- 25 lamps, bicycle-lanterns, and the like.

The generator comprises a two-part case, of 30 which A represents the lower part or generating-chamber, and B the upper part or wa- ter-reservoir, the two parts being joined to- 35 gether by means of the screw-coupling a. The water-reservoir is provided with a dia- phragm b, which forms the bottom of the res- ervoir. Within the generating-chamber A is placed the carbid-cartridge C, which car- 40 tridge is described more particularly in Let- ters Patent No. 610,937, issued to me on the 20th day of September, 1898, for improve- 45 ments in acetylene-gas generators. Briefly, this cartridge comprises a body of broken car- bid put up within a shell D and having its mass broken up into small portions by layers of an absorbent material projecting out from the central core E of the same material. This cartridge slips down within the generating- 50 chamber A around the stand-pipe F, which is centrally positioned within said chamber by means of the socket f, which engages the post G, attached to the bottom of the cham- ber. The stand-pipe is provided with small 55 holes f' near the bottom, and the water is de- livered through these holes to the absorbent

core E, from which it passes, by means of the absorbent layers, into the mass of the carbid.

H represents the feed-pipe, which delivers water from the reservoir to the stand-pipe. 55 This feed-pipe has its origin in the valve-case I, where it registers with the valve-seat i, which is conical in shape to receive the needle-valve, as represented in the drawing. The valve-case is provided with a screw-cap 60 J, through which the valve-stem K is screwed. A stuffing-box L at the outer extremity of the cap J provides a water and gas tight connec- 65 tion about the valve-stem. In the lower part of the valve-case I is a small check-valve M, which opens upwardly, thus allowing the wa- ter to enter the valve-case and preventing the backflow of gas into the water-reservoir.

N represents a secondary gas-chamber in communication with the generating-chamber 70 A, into the top of which it enters through the diaphragm b. This secondary gas-chamber has a capacity for storing up a considerable quantity of gas, being proportioned relatively to the size of the generator. At the top it is 75 provided with an offset O, from which the nipple P passes through the center of the top of the reservoir. A flanged collar Q screws down upon this nipple and makes a tight joint at this point. The burner-tip R fits into 80 the top of this collar Q, and the lamp-globe or lantern-headlight may be attached to the generator in proper position relative thereto. As this forms no part of my present inven- 85 tion, it has not been deemed necessary to illus- trate it herein. The foot of the secondary gas-chamber where it enters the generating-chamber is provided with a hollow screw-plug S, from the bottom of which projects a small drip-cup s. The plug proper, S, is filled with 90 a stopper T, of felt or other suitable porous material. The drip-cup s is provided with the restricted gas-inlets U U and the water or drip outlet V. Finally, the water-reservoir is provided with a filler-plug W, into which is 95 screwed the vent-plug X.

The operation of this generator is as fol- 100 lows: The cartridge having been placed in the generating-chamber about the stand-pipe, as illustrated, and the water-reservoir hav- ing been filled from the filler-plug opening, the valve is opened by giving the valve-stem

K a small turn to the left. Ordinarily a quarter-turn will provide the necessary amount of feed. The water from the reservoir rises into the valve-chamber through the check-valve M and passes through the feed-pipe H to the center of the stand-pipe, wherein it descends and passes out through the opening f', whence the water flows to the absorbent core and is disseminated immediately throughout the mass of the carbid. The gas as generated rises through the opening in the top of the cartridge around the stand-pipe, the moisture contained in the gas being first condensed as it comes in contact with the bottom of the diaphragm b, whence the water of condensation drips back into the bottom of the generating-chamber. The gas thus partially deprived of its moisture enters the top of drip-cup s in plug S through the restricted passages U, in passing through which a further separation of moisture takes place, which runs down the outside of the cup. The gas then rises through the felt stopper T, by which it is deprived of all remaining moisture and thoroughly dried. The moisture intercepted by the stopper T runs back down the drip-cup, whence it issues back into the generating-chamber through the drip-vent V. The dried gas then accumulates in the secondary gas-chamber N, where it is cooled by the water which surrounds said chamber. As soon as the air contained in the generator has been driven out by the accumulating gas the gas then issuing from the burner-tip may be lighted, and the lamp will continue to burn until the water-supply is cut off. While the generator is in operation, the vent-plug X must be raised, so as to place the top of the reservoir in communication with the atmosphere. Should there be an overgeneration of gas, there will be a back pressure in the generating-chamber, which will force the water in feed-pipe H back in the valve-case until the check-valve M is closed, where the water will be held until the gas-pressure is lowered by consumption at the burner. The closing of the check-valve M prevents the entrance of gas into the water-reservoir and its escape thence through the vent-plug X. The operation of the generator is entirely automatic, and the gas is produced steadily, being delivered to the burner in a thoroughly dried and cooled condition.

The plug S and stopper T constitute what I term a "moisture-separator" and form the 55 most essential feature of my present improvements. The stopper may be renewed from time to time as it becomes saturated with the impurities, which it also removes from the gas. This renewal is accomplished quickly 60 by unscrewing the plug S, the bottom of the drip-cup being notched to receive a screw-driver for this purpose. In fact, it will be seen that all parts of my generator are so arranged as to be quickly and readily got at for 65 cleansing purposes.

Having thus described my improvements, what I claim as my invention, and desire to secure by Letters Patent, is—

1. In a gas-generator, the combination with 70 the generating-chamber and the gas-outlet therefrom, of a stopper of felt or other porous material in the entrance to said outlet, a drip-cup below said stopper, and gas and water passages in said drip-cup, substantially as 75 and for the purpose set forth.

2. In a gas-generator, the combination of a generating-chamber, a water-reservoir above the generating-chamber, a valved passage between the two, a secondary gas-chamber with 80 in the water-reservoir, a hollow screw-plug closing the entrance from the generating-chamber to the secondary gas-chamber, a porous stopper in said plug, a drip-cup depending from said plug, a restricted gas-passage 85 leading into the upper part of said cup and a water-outlet at the bottom of said cup.

3. In a gas-generator, the combination with the generating-chamber A and water-reservoir B, of the secondary gas-chamber N with 90 in said reservoir, said chamber N having its origin at one side of the center of the generating-chamber and having an offset O by which its outlet is brought to the center of the reservoir, the moisture-separator comprising 95 the plug S and the stopper T at the entrance to the secondary gas-chamber, and the central valve-controlled feed-pipe H, substantially as described.

In testimony whereof I have affixed my signature in presence of two witnesses.

FRANK E. BUNDY.
